CLAIM

The ornamental design for a metal end component of a spool for wire and the like as shown and described.

DESCRIPTION

FIG. 1 is a perspective view of a first embodiment of the metal end component of a spool for wire or the like; the opening encircled by the stippled line and referenced as “FIG. 2” being part of the design;

FIG. 2 is an enlarged fragmentary view of the opening in FIG. 1;

FIG. 3 is a cross sectional view taken along line 3-3 of FIG. 2;

FIG. 4 is a perspective view of the metal end component of a spool for wire or the like of FIG. 1 as seen from the opposite side, the opening encircled by the stippled line and referenced as “FIG. 5” being part of the design;

FIG. 5 is an enlarged fragmentary view of the opening in FIG. 4;

FIG. 6 is a perspective view of a second embodiment of the metal end component of a spool for wire or the like, the opening encircled by the stippled line and referenced as “FIG. 7” being part of the design;

FIG. 7 is an enlarged fragmentary view of the opening in FIG. 6;

FIG. 8 is a cross sectional view taken along line 8-8 of FIG. 7;

FIG. 9 is a perspective view of the metal end component of a spool for wire or the like of FIG. 6 as seen from the opposite side, the opening encircled by the stippled line and referenced as “FIG. 10” being part of the design; and, FIG. 10 is an enlarged fragmentary view of the opening in FIG. 9.

The broken lines in the drawings depict environmental subject matter only and form no part of the claimed design.

The stippled lines (long dash followed by a dot and a long dash) do not form part of the design. The dashed lines (dashes only) show boundary.
